EX
95 9 6,792

UNITED STATES PATENT OFFICE

HENRY BOOT, OF PHILADELPHIA, PENNSYLVANIA, ASSIGNOR TO THOMAS DOLAN & CO., OF SAME PLACE.

DESIGN FOR NUBIA.

Specification forming part of Design No. 6,792, dated August 5, 1873; application filed June 28, 1873.

D.

To all whom it may concern:

Be it known that I, HENRY BOOT, of Philadelphia, county of Philadelphia, State of Pennsylvania, have invented a Design for a Nubia, of which the following is a specification:

The figure in the accompanying drawing represents sufficient of the body A and border or edging B of a nubia to illustrate my design.

The body A consists of plain knitted work a, across which at regular intervals extend parallel ribs b, and a full appearance may, if desired, be imparted to the said body by puffing the same in the manner clearly shown in the drawing.

The border or edging B consists of a series of narrow transverse ribs, each composed of a series of rounded loops, as shown.

Irrespective of the colors employed, I claim—

1. The design for the body A of the nubia, substantially as shown and described.
2. The design for the whole nubia, including the body A and border or edging B.

In testimony whereof I have signed my name to this specification in the presence of two subscribing witnesses.

HENRY BOOT.

Witnesses:

CLINTON M. LATOURETTE,
LEWIS T. GODFREY.
